UNITED STATES PATENT OFFICE.

CHARLES H. HUTCHINS, OF DETROIT, MICHIGAN.

DOUBLE CAR-ROOF.

SPECIFICATION forming part of Letters Patent No. 624,654, dated May 9, 1899.

Application filed February 6, 1899. Serial No. 704,627. (No model.)

To all whom it may concern:

Be it known that I, CHARLES H. HUTCHINS, a citizen of the United States, residing in Detroit, in the county of Wayne and State of Michigan, have invented a new and useful Improvement in Double Car-Roofs, of which the following is a specification.

My invention relates to the construction of roofs for railway-cars, and more particularly to the kind of car-roofs commonly known as "double" car-roofs, wherein an inner roof of sheet metal is combined with an outer roof of wood.

Double car-roofs or combined sheet-metal and wood car-roofs have heretofore usually been constructed of three general types or classes—first, where it is attempted to combine both the sheet-metal roof and the wood roof with one and the same main roof frame—by laying the roof-boards and the metal roof-plates one directly on top of the other and nailing or securing the roof-boards through the metal plates to the single roof-frame. Roofs of this general class are illustrated, for example, in the patents to Wands, Nos. 153,868 and 302,452, or Aldridge, Nos. 194,286 and 221,142. In combined wood and metal roofs of this type or class the metal roof or covering may have the important practical advantage of being continuous, the edges of the adjacent wide metal plates overlapping each other; but the metal roof is necessarily perforated with numerous nail or other holes liable to form leaks and the metal and wood roofs are necessarily rigidly united together, thus destroying the natural flexibility of the wood roof-frame and its capability to successfully withstand the shocks and jars and the weaving and torsional strains and motions to which it is subjected in use. In another or second class or type of combined wood and metal car-roofs an outer continuous covering of boards and an inner non-continuous or partial covering of wide sheet-metal plates covering the space between the carlines are combined with a single or main roof-frame, as illustrated, for example, in the patent to Smith, No. 325,634. In roofs of this class the sheet-metal plates of the inner or metal roof are not necessarily perforated by the nails which secure the outer roof-boards in place; but this construction does not form a

continuous metal roof, as the metal sheets only extend longitudinally from one carline to another and simply cover the series of 55 spaces between the carlines, thus necessarily losing the great object or advantage of a continuous and complete sheet-metal covering of wide and non-disengagable sheets or plates, while the metal plates thus fitting between 60 the carlines necessarily also form a destructively-rigid union between the metal roof and the wood or board roof and the roof-frame, and the shocks and jars and torsional and weaving strains and motions to which the 65 roof is subjected in use tend to dislodge the edges of the metal plates from the grooves in the carlines or roof-frames in which they fit, thus causing leaks and speedily destroying the integrity of the roof. This construction 70 is also comparatively complicated and expensive, requiring a great deal of time and labor, care, and accuracy, as the carlines and roof-frame require not only to be specially grooved and fitted and accurately sized and 75 arranged or spaced, but the sheet-metal plates also require to be cut and formed to corresponding special sizes and shapes, and any inaccuracy or disproportion of parts necessarily causes defective construction. In 80 still another or third class or type of combined sheet-metal and wood car-roofs, as shown, for example, in the patents to Jennings, No. 512,087, or Williamson and Pries, No. 584,836, attempts have been made to 85 practically combine together an inner sheet-metal roof with an outer roof through the agency of two superimposed roof-frames, one upon which the sheet-metal plates of the inner metal roof are laid and the other upon 90 which the boards of the outer wood roof are laid. In this latter class or type of combined wood and sheet-metal car-roofs the inner sheet-metal roof is not continuous, the sheet-metal plates extending simply from one carline to another, the carlines being provided with grooves to receive the edges of the metal plates, and the metal plates thus fitting between the carlines necessarily rendering the structure rigid and destroying the flexibility of the roof-frame. Car-roofs of this double-roof-frame type are thus subject to most, if not all, the defects, difficulties, and objections of the second class or type just 95 100

before mentioned, wherein a single roof-frame is employed, and to the further difficulty or objection that the outer wood roof and its frame are exceedingly liable in practice to be 5 wrenched off the car by high winds or by air-suction when the train is in rapid motion, and to the further defect that the outer roof-frame, while adding to the expense or cost, is not so combined with the main roof-frame, 10 as to give any material additional strength or flexibility thereto, and generally it may be stated that in all combined sheet-metal and wood car-roofs heretofore in use, wherein the construction is such as to rigidly unite the 15 metal plates to the single roof-frame, or to either one of the two roof-frames where a double roof-frame is employed, the jars and shocks to which the cars are subjected and the torsional, weaving, and buckling strains 20 or motions communicated to the car-roof in use tend greatly to destroy the integrity of both the metal roof and the wood roof, causing cracks and leaks therein and speedily impairing the whole structure, and where the 25 metal plates of the metal roof are fitted or mortised into grooves in the carlines or framework of the roof they necessarily form a structural bracing element of the car-roof frame, destroying its flexibility and capability of suc- 30 cessfully withstanding the shocks, jars, and torsional and weaving strains and motions to which it is subjected, and in all constructions of combined sheet-metal and wood car-roofs heretofore in use, wherein a double 35 roof-frame is employed with a sheet-metal covering between, great difficulty has always been experienced in properly securing or anchoring the upper wood roof in place, such outer covering being frequently wrench- 40 ed from the car by violent winds or by air-suction produced by the rapid motion of the train, as before stated.

The object of my invention is to provide a simple, economical, efficient, durable, and 45 practical construction of combined sheet-metal and wood car-roof, which will successfully overcome all the difficulties heretofore experienced in practically combining into a single unitary structure a sheet-metal and 50 wood roof for cars. In other words, it is my object to so combine the sheet-metal roof with the wood roof and frame that the structure as a whole will preserve the flexibility of the wood roof the same as though a tar composition or plastic roof were used in connection therewith instead of a sheet-metal roof; also, 55 to so combine the sheet-metal roof with the main roof-frame and the super roof-frame that the car or roof as a whole will have the full 60 strength and flexibility due to the two roof-frames, while at the same time the two roof-frames shall be so connected together that all 65 possibility of the outer board roof being lifted from the car by wind or air-suction shall be effectually prevented, and at the same time enable any individual sheet or plate of the metal roof to be independently removed and

replaced for the purpose of repairs without disturbing the other plates or the board roof or either of the two roof-frames.

My invention consists in the means I employ to overcome the aforesaid difficulties and objections and to accomplish the object or result above mentioned; that is to say, it consists in the combination, with a main roof-frame comprising carlines and purlins, a ridge-purlin, a plate and facia, all properly framed and secured together, of a super roof-frame comprising carlines and purlins and a ridge-purlin, a continuous sheet-metal roof 75 comprising a series of loose independently-removable sheets or plates extending from the ridge to the eaves between said main roof-frame and said super roof-frame, the side edges of the adjacent metal plates being joined together by loose high standing joints consisting in a high upright flange on the edge of one plate and a high upright inverted - U - shaped fold on the meeting edge of the adjacent sheet or plate, whereby the sheets are 80 kept from all possibility of becoming disengaged or disjoined one from another, so that the sheet-metal covering may always be maintained absolutely continuous and complete 85 without break or leak throughout and over 90 the whole roof, while at the same time the individual sheets or plates of this continuous metal roof are left loose and free to move or yield in respect to each other and to both the main roof-frame and the super roof-frame to 95 the extent necessary to preserve the full natural flexibility of said frames and prevent 100 injury thereto or to the metal roof or its joints, said super roof-frame having the boards of the wood roof nailed thereto and being itself 105 firmly anchored or secured to the main roof-frame by bolts extending through the main facia and the supercarlines at the eave ends thereof and, further, bolts extending centrally through the main and super ridge- 110 purlins between the ends of the oppositely-inclined metal plates on the two sides of the roof. The main roof-frame and the super roof-frame are thus firmly and adequately 115 secured together, so that there is no possibility of any wind or air-suction wrenching the outer wood roof from the car and so that the roof as a whole is given the full or combined strength and flexibility of both roof-frames, 120 each roof-frame supplementing and coöperating with the other, while at the same time the continuous metal roof between the upper and lower roof-frames is itself loose and flexible, being composed of a series of loosely-joined 125 but non-disengageable sheets acting somewhat on the principle of the links of a chain and in no way tending to render rigid or brace the roof-frames or destroy their natural flexibility. The bolts extending through the main facia and the lower ends of the supercarlines also extend through the lower ends of the metal plates of the continuous flexible sheet-metal roof, one bolt extending through 130 each metal plate. The single bolt extending

through the plate near its lower end leaves the plate substantially free under any limited movement necessary to prevent undue strains upon the roof and to prevent the metal plates from having a brace effect upon either the upper or lower roof-frame. To permit the roof plates to be independently removed and replaced with ease, the supercarlines are located intermediate of the main carlines, so that the metal roof-plates are not clamped directly between the main carlines and supercarlines, as would be the case if the supercarlines were placed directly above the main carlines.

As in my invention the sheet-metal roof is continuous and flexible by reason of the loose standing joints joining the meeting edges of adjacent sheets, all necessary flexibility to prevent giving undue rigidity to the roof as a whole being thus secured, I am enabled to employ flat metal sheets as contradistinguished from corrugated sheets which have heretofore generally been employed in metal roofs, the corrugations in the sheet metal being intended to give some degree of yield to the sheet metal in the direction of the plane of the roof. This results in a very material saving in the cost of construction, as my flat plates require about ten per cent. less material than the corrugated plates. In the construction of my double car-roof it will also be observed that the carlines and supercarlines may be placed any desired or varying distances apart, requiring no extreme accuracy of construction or of size or shape and no special configuration or shaping of the parts composing the frames, and that the sheet-metal plates are also very simple of construction and require no special fitting between the parts of the frame, as they extend continuously in the same plane between the two roof-frames. My roof is therefore of a very simple and cheap construction and may be rapidly built or put together with little labor.

My invention also consists in the novel construction of parts and devices and in the novel combinations of parts and devices herein shown and described, and specified in the claims.

In the accompanying drawings, forming a part of this specification and in which similar letters of reference indicate like parts throughout all the views, Figure 1 is a plan view of a portion of a car-roof embodying my invention, the outer or wood roof being in part removed. Fig. 2 is a vertical cross-section on line 2 2 of Fig. 1. Fig. 3 is a vertical cross-section on line 3 3 of Fig. 1; Fig. 4, a longitudinal section on line 4 4 of Fig. 1, and Fig. 5 is an enlarged detail view of the joint uniting the meeting edges of adjacent plates of the sheet-metal roof.

In said drawings, A represents the car-body or its frame, A' the eaves-plates, and A² the siding.

65 The main roof-frame comprises the main carlines B, the main purlins C, the ridge-purlin C', and the main facia D, all these parts

being securely framed or united together and to the car-body or its frame in the usual or customary manner.

Above the main roof-frame is a supplemental or super roof-frame comprising supercarlines F, superpurlins G, and a ridge-purlin G.

H is a continuous flexible sheet-metal roof fitting and extending continuously between the main roof-frame and the super roof-frame and composed of a series of metal plates each extending from the eave to the ridge of the roof and flexibly joined together at their meeting side edges by high standing joints h h'. As will be seen from the drawings, each of the high standing joints h h' comprises a high upright flange h on the edge of one sheet and an inverted-U fold h' on the meeting edge of the adjacent sheet. Each metal plate or sheet thus has a high upright flange h on one side edge and a corresponding inverted-U fold h' on its opposite edge. The flange h and fold h' are preferably made about three-fourths of an inch in height, so that no shock, jar, or torsional or weaving strain or motion to which the car or roof may be subjected can operate to disengage the two members of the loose joint. The space between the two limbs of the U fold h' should be two or three times the thickness of the sheet metal, so as to give ample room for all necessary movements of the roof-plates in respect to each other under strains or shocks or expansion and contraction due to changes in temperature, and thus prevent all danger of injury either to the wood roof or the metal roof or the roof-frames or car as a whole from any shocks or strains to which the car may be subjected. The inverted-U fold h' and flange h also afford smooth guides for the individual plates or sheets of the roof in slipping the same individually or independently in and out for repairing or other purposes.

As will be seen from the drawings, the supercarlines F are preferably intermediate or not directly above the main carlines B, so that the main and super carlines will not have any direct clamping or binding effect upon the sheet-metal plates H tending to interfere with the easy removal or replacement of the sheets independent of each other. By combining the independently-removable sheet-metal roof-plates with the main frame and superframe in this manner, with the supercarlines intermediate of the main carlines, the flexibility of the sheet-metal roof-plates enables them to be readily removed from between the two frames. The loose standing joints h h' are also preferably located intermediate of and not adjacent to the supercarlines F, as the standing joints and the supercarlines thus divide the sheet-metal roof into comparatively narrow spaces or troughs to convey down and out any dirt, cinders, or other material that may accumulate between the wood roof and the sheet-metal roof. By this particular arrangement and combination of parts also the standing joints will have no

binding effect against the supercarlines in removing or replacing the sheet-metal plates H.

The supercarlines F extend out or down beyond the outer edge of the main facia D 5 sufficiently to leave a space X between the main facia D and a superfacia K, which is nailed or otherwise secured directly to said projecting ends f of the supercarlines F. This space X leaves room for the water, dirt, 10 and cinders that may collect on the inner or sheet-metal roof to pass out freely. A down-turned flange h² is turned at the lower edge of the sheet-metal plates.

M are removable bolts extending through 15 the outer superpurlin C and the lower ends of the supercarlines F and the main facia D. These bolts are furnished with threaded nuts m at their lower ends and securely anchor the superframe to the main frame at the 20 eaves. The bolts M have slotted or other heads m', adapted to be turned from above, so that the nuts m may have one side to abut directly against the siding A², and thereby be prevented from turning or unscrewing. 25 The bolts M pass through suitable holes h³, provided for the purpose, one in each of the metal plates of the metal roof. The bolts thus serve to prevent the metal plates from slipping down or outward. The ridge super- 30 purlin G' is notched or gained at g to receive the supercarlines F, and also at g' to receive the standing joints h h' of the sheet-metal roof.

N N are the bolts which extend through 35 the main ridge-purlin c' and the super ridge-purlin G' between the meeting ends of the oppositely-inclined metal plates H H of the sheet-metal roof, the same being provided with threaded nuts n n.

40 P P are the bolts extending horizontally through the plates A' and the main facia D, thus securely uniting the main facia to the car-body frame.

R is the foot-board, and R' the sill-hooks, 45 supporting the same.

T is the wood roof, composed of matched boards nailed to the superpurlins G.

The loose standing joints h h' with which 50 each sheet-metal plate is furnished not only serve to loosely and non-disengageably connect the series of sheet-metal plates composing the flexible sheet-metal roof together, but they serve to individually strengthen and stiffen each separate independent sheet-metal 55 plate of the roof, thus securing the advantage in point of strength of corrugated plates at a substantial saving in material.

To repair or remove and replace any particular sheet-metal plate of the roof, all that 60 is required to be done is to remove the outer facia in whole or in part and then take out the bolt M, which extends through the particular sheet-metal plate to be removed, when said plate can be readily slipped out and re- 65 paired or replaced with a new one.

The loose high-standing joints h h', which 70 flexibly and loosely connect the plates H H

of the metal roof at their side edges, are, as will be seen from the drawings, substantially equal in height to the thickness of the supercarlines F, which extend in the same direction as and parallel to said joints, so that the superpurlins G prevent all possibility of the members h h' of the high-standing joints becoming disengaged under any shocks or 75 strains to which the car or its roof may be subjected in use.

The metal plates H at the ends of the car-roof are preferably furnished with down-turned flanges h² to overlap the end face-board S, said flange fitting between the face-board S and the upper face-board S' at the 80 ends of the car.

I claim—

1. In a car, the combination with a main 85 roof-frame united to the frame of the car and comprising carlines and purlins and a ridge-purlin, of a super roof-frame comprising carlines and purlins and a ridge-purlin, a board roof secured to said superframe, and 90 a continuous sheet-metal roof composed of a series of independently-removable metal plates extending from the eave to the ridge between said main frame and superframe, said metal plates being joined directly to 95 together at their adjacent edges by loose standing joints adapted to permit the necessary movement of the plates in respect to each other to prevent injury thereto or to the roof as a whole and also to permit each metal 100 plate to be removed or inserted without disturbing the others or said wood roof or superframe, and removable bolts extending through the lower ends of said supercarlines and uniting the same to the eave-plate or 105 facia of the main frame, said removable bolts having threaded nuts substantially as specified.

2. In a car, the combination with a main 110 roof-frame united to the frame of the car and comprising carlines and purlins and a ridge-purlin, of a super roof-frame independent of and not framed into said main roof-frame and comprising carlines and purlins and a ridge-purlin, a board roof secured to 115 said superframe, and a continuous sheet-metal roof composed of a series of independently-removable flat metal plates extending from the eave to the ridge between said main frame and superframe, said metal plates being joined together at their adjacent edges by loose standing joints adapted to permit the necessary movement of the plates in respect to each other to prevent injury thereto or to the roof as a whole and also to permit 120 each metal plate to be removed or inserted without disturbing the others or said wood roof or superframe, and consisting of a high upright flange on the sheet and a corresponding inverted-U fold on the meeting edge of 125 the adjacent sheet, and bolts extending centrally through said main ridge-purlin and said super ridge-purlin between the ends of 130 the oppositely-inclined metal plates, and re-

movable bolts extending through said lower ends of said supercarlines and uniting the same to the eave-plate or facia of the main frame, said removable bolts having threaded nuts substantially as specified.

3. In a car, the combination with a main roof-frame united to the frame of the car and comprising carlines and purlins and a ridge-purlin, of a super roof-frame comprising carlines and purlins and a ridge-purlin, a board roof secured to said superframe, and a continuous sheet-metal roof composed of a series of independently-removable flat metal plates extending from the eave to the ridge between said main frame and superframe, said metal plates being joined together at their adjacent edges by loose standing joints adapted to permit the necessary movement of the plates in respect to each other to prevent injury thereto or to the roof as a whole and also to permit each metal plate to be removed or inserted without disturbing the others or said wood roof or superframe, a main facia attached to the main frame, bolts extending through said main facia and said supercarlines, and a facia attached to the super roof-frame, said removable bolts having threaded nuts substantially as specified.

4. In a car, the combination with a main roof-frame united to the frame of the car and comprising carlines and purlins and a ridge-purlin, of a super roof-frame comprising carlines and purlins and a ridge-purlin, a board roof secured to said super roof-frame, and a continuous sheet-metal roof composed of a series of independently-removable metal plates extending from the eave to the ridge between said main frame and superframe, said metal plates being joined together at their adjacent edges by loose standing joints adapted to permit the necessary movement of the plates in respect to each other to prevent injury thereto or to the roof as a whole and also to permit each metal plate to be removed or inserted without disturbing the others or said wood roof or superframe, bolts extending centrally through said main ridge-purlin and said super ridge-purlin between the ends of the oppositely-inclined metal plates, removable bolts extending through said lower ends of said supercarlines and uniting the same to the main facia secured to the eave-plates of the main frame, and a facia attached to the projecting ends of the supercarlines of the super roof-frame, said removable bolts having threaded nuts substantially as specified.

5. In a car, the combination with a main roof-frame united to the frame of the car, of a super roof-frame, a board roof secured to said super roof-frame, and a continuous sheet-metal roof composed of a series of independently-removable metal plates fitting between said frames and extending continuously from end to end of the car and from the eave to the ridge, said metal plates being joined directly together at their adjacent edges by loose standing joints adapted to permit the

necessary movement of the plates in respect to each other to prevent injury thereto or to the roof as a whole and also to permit each metal plate to be removed or inserted without disturbing others or said wood roof or superframe, the carlines of the superframe being intermediate and not directly above the carlines of the main frame, substantially as specified.

6. In a car, the combination with a main roof-frame united to the frame of the car, of a super roof-frame, a board roof secured to said super roof-frame, and a continuous sheet-metal roof composed of a series of independently-removable metal plates fitting between said frames and extending continuously from end to end of the car and from the eave to the ridge, said metal plates being joined directly together at their adjacent side edges by loose standing joints adapted to permit the necessary movement of the plates in respect to each other to prevent injury thereto or to the roof as a whole and also to permit each metal plate to be removed or inserted without disturbing others or said wood roof or superframe, the carlines of the superframe being intermediate and not directly above the carlines of the main frame, the carlines of the superframe having projecting ends extending beyond the main facia, a main facia secured to the frame-plates of the car, and a superfacia secured to the ends of the supercarlines thus leaving a space between the superfacia and the main facia for the escape of water, dirt and cinders, substantially as specified.

7. In a car, the combination with a main roof-frame, of a super roof-frame having supercarlines and superpurlins and a board roof secured thereto, and a continuous sheet-metal roof fitting between said roof-frames and composed of a series of independently-removable metal plates joined directly together at their adjacent side edges by loose standing joints consisting each of a high upright flange and an inverted-U fold on the edges of adjacent plates, said standing joints and supercarlines together dividing the sheet-metal roof into a series of narrow spaces or troughs, substantially as specified.

8. In a car, the combination with a main roof-frame, of a super roof-frame having supercarlines and superpurlins and a board roof secured thereto, and a continuous sheet-metal roof fitting between said roof-frames and composed of a series of independently-removable metal plates joined directly together at their adjacent side edges by loose standing joints consisting each of a high upright flange and an inverted-U fold on the edges of adjacent plates, said standing joints and supercarlines together dividing the sheet-metal roof into a series of narrow spaces or troughs, and bolts extending through the eave ends of the supercarlines and the facia of the main frame, substantially as specified.

9. In a car, the combination with a main

- 5 roof-frame, of a super roof-frame having supercarlines and superpurlins and a board roof secured thereto, and a continuous sheet-metal roof fitting between said roof-frames and composed of a series of independently-removable metal plates joined directly together at their adjacent side edges by loose standing joints consisting each of a high upright flange and an inverted -U fold on the edges of adjacent 10 plates, said standing joints and supercarlines together dividing the sheet-metal roof into a series of narrow spaces or troughs, bolts extending through the eave ends of the supercarlines and the facia of the main frame, and bolts extending through the ridge-purlins of said main and super frames between the meeting ends of the oppositely-inclined metal plates of the metal roof, substantially as specified.

15 20 10. In a car, the combination with a main roof-frame, of a super roof-frame having supercarlines and superpurlins and a board roof secured thereto, and a continuous sheet-metal roof fitting between said roof-frames and composed of a series of independently-removable metal plates joined directly together at their adjacent side edges by loose standing joints consisting each of a high upright flange and an inverted -U fold on the edges of adjacent 25 plates, said standing joints and supercarlines together dividing the sheet-metal roof into a series of narrow spaces or troughs, bolts extending through the eave ends of the supercarlines and the facia of the main frame and the lower ends of the metal plates of the metal roof, substantially as specified.

30 35 11. The double car-roof comprising a main frame, a superframe covered with roof-boards, and a continuous loose flexible sheet-metal roof fitting between said main and super frames and extending continuously from end to end of the car and from eave to ridge without bracing connection with either of said frames and composed of a series of independently-removable plates loosely and flexibly joined together at their meeting side edges by high standing joints consisting each of a high upright integral flange on one sheet and an integral open inverted-U fold on the adjacent sheet, and removable bolts having threaded nuts extending through the lower ends of said metal plates and connecting said main and super frames together at the eaves thereof, substantially as specified.

40 45 50 55 60 12. The double car-roof comprising a main frame, a superframe covered with roof-boards, and a continuous loose flexible sheet-metal roof fitting between said main and super frames and extending continuously from end to end of the car and from eave to ridge without bracing connection with either of said frames and composed of a series of independently-removable plates loosely and flexibly joined together at their meeting side edges by high standing joints consisting each of a high upright integral flange on one sheet and an integral open inverted-U fold on the adjacent sheet, and removable bolts having threaded nuts extending through the lower ends of said metal plates and connecting said main and super frames together at the ridge thereof, said bolts extending between the meeting ends of the oppositely-inclined metal plates at the ridge, substantially as specified.

65 70 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950
